UNITED STATES PATENT OFFICE.

HARRY T. ANDERSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CANE-CAR.

1,380,176.

Specification of Letters Patent. Patented May 31, 1921.

Application filed January 10, 1921. Serial No. 436,260.

To all whom it may concern:

Be it known that I, HARRY T. ANDERSON, a citizen of the United States, and resident of Butler, in the county of Butler and State 5 of Pennsylvania, have invented a new and useful Improvement in Cane-Cars; and I do hereby declare the following to be a full, clear, and exact description thereof.

My invention relates to railway cars having transverse partitions and relates particularly to cars for carrying sugar cane.

The object of my invention is to provide an improved partition construction for cars of the above indicated character and the 15 essential feature of novelty consists in the use in these partitions of side posts built up of two Z-bars placed back to back, the partition boards being bolted to the flanges formed by the coacting arms of the two 20 Z-bars.

The advantages obtained by this construction are that the space taken up by the partition is reduced to a minimum as compared with the space taken up by the partitions 25 when the ordinary channel construction is used. Also, my improved construction reduces by one-half the number of bolts required in applying the partition boards and consequently decreases the labor cost. Other 30 advantages will appear from the following description.

A cane car constructed in accordance with my invention is shown in the accompanying drawings, in which Figure 1 is a side 35 elevational view, with parts broken away and other parts shown in section, of the complete car; Fig. 2 is a vertical cross sectional view taken on the line 2—2, Fig. 1; Fig. 3 is a horizontal view of one of the 40 transoms of the car showing two partition side posts constructed in accordance with my invention; and Fig. 4 is an enlarged fragmentary section showing one of the side posts of Fig. 3 with the partition boards in 45 place.

The car shown in the drawing comprises the usual side sills 2, center sill 3, body bolster 4, swinging doors 5, and door-operating mechanism 6, and the body of the car 50 is made up of vertical angle bars 7 bolted to the side sills 2 and to angle bars 8 at the top of the sides and ends of the car. These parts are of ordinary construction and are here shown only for the purpose of illustrating my invention, which is concerned 55

particularly with the construction of the partitions 10 which divide the car into three compartments, usually twelve feet in length.

Each of the partitions 10 consists of a 60 double sheathing of planks 11 laid horizontally with their ends bolted to side posts, the construction of which is best shown in Figs. 3 and 4. Each of these side posts consists of two Z-bars 12 placed back to back, 65 with their corresponding flanges 13 in contact. The planks 11 are placed against these flanges 13 and are fastened in place by means of bolts 14 which pass through both planks and both flanges. The bolts are preferably countersunk, as shown at 15, so that the total thickness of the partition consists only of the combined thickness of the two 70 planks and the two flanges 13 of the side posts.

This construction provides convenient means for connecting the side posts 10^a to the frame of the car by means of gusset plates 16 which, as shown in Figs. 2, 3 and 4, are riveted to the transoms 17 and to 80 the flanges 13.

My present invention is an improvement over the partition construction in which the side posts are made up of channel bars. Where the ordinary channel construction is 85 used, a 4 inch channel bar is the minimum size that can be practically employed. This, with the use of 1½ inch planks, makes the total thickness of the partition 7 inches. Where a 6-inch channel is used, the total 90 thickness of the partition is nine inches. In my improved construction the combined thickness of the two planks and the two flanges of the Z-bars is 3½ inches, thus making a reduction of 3½ inches in comparison 95 with the channel construction where 4-inch channels are used, and a reduction of 5½ inches in comparison with the channel construction in which 6-inch channels are used.

In addition to the saving in space produced in my invention I also greatly increase the strength of the side posts without increasing their weight.

It will also be observed that the partition planks 11 are fastened to the side posts by 105 one-half the number of bolts that are required in the channel construction. When the planks are bolted to channel bars, each plank is separately bolted to one flange of the side post, two bolts being required at 110

each end of each plank. With my improved construction each plank is also fastened with two bolts, but the bolts also serve to attach the plank on the opposite side of the flanges 5 13, as shown in Fig. 4. The time and cost of assembling the partitions is thus greatly reduced.

My improved partition construction may be employed in cars other than cane cars 10 where partitions are required, and the details of construction shown in the drawing and described above may be varied in many respects without departing from my invention, the scope of which is indicated in the 15 appended claims.

I claim as my invention:

1. A railway car having a partition comprising side posts each composed of two Z-bars having corresponding flanges placed together and planks secured to the said flanges.
2. A railway car having a partition comprising side posts each composed of two Z-bars having corresponding flanges placed together, planks resting against the opposite sides of the said flanges, and bolts extending through the said flanges and through the said planks.
3. A railway car having a partition comprising vertical side posts each composed of

two Z-bars having corresponding flanges placed together, planks extending horizontally between the said side posts, and bolts extending through the said flanges and through the said planks.

35

4. A railway car having a partition comprising vertical side posts each composed of two Z-bars having corresponding flanges placed together, planks extending horizontally between the said side posts on both 40 sides of the said flanges, and bolts extending through the said flanges and through the said planks.

40

5. A railway car having a partition comprising vertical side posts each consisting of 45 two Z-bars having corresponding flanges placed together, gusset plates bolted to the said flanges and to the frame of the car, planks extending horizontally between the said side posts and resting against both sides 50 of the said flanges, and bolts extending through the said flanges and through the said planks.

50

In testimony whereof I, the said HARRY T. ANDERSON, have hereunto set my hand.

55

HARRY T. ANDERSON.
